(57) **ABSTRACT**

'NCMH2' is a new cultivar of *Mahonia* with a compact
habit, narrow evergreen foliage, showy red and yellow
flowers and red new foliage color.

2 Drawing Sheets

1

Latin name of the genus and species: The Latin name of
the novel, ornamental plant variety disclosed herein is
Mahonia.

Variety denomination: The inventive cultivar of *Mahonia*
disclosed herein has been given the varietal denomination
'NCMH2'.

BACKGROUND OF THE INVENTION

The present invention comprises a new and distinct
Mahonia cultivar hereinafter referred to by the cultivar name
'NCMH2'. This new *Mahonia*, 'NCMH2', was selected
from a population of seedlings grown from an open-pollinated
hybrid NCSU H2009-018-063 (unpatented). The first
asexual propagation of 'NCMH2' was carried out in December
2014 by rooting stem cuttings in Mills River, N.C. and
has been asexually reproduced repeatedly by vegetative
cuttings over a 5-year period. 'NCMH2' roots from semi-
hardwood and hardwood cuttings were treated with a basal
dip of 6,000-10,000 ppm indole butyric acid (potassium salt)
in water. 'NCMH2' has been found to retain its distinctive
characteristics through successive asexual propagations.

SUMMARY OF THE INVENTION

'NCMH2' is distinguishable from other *Mahonia* cultivars,
when grown under standard horticultural practices in
Mills River, N.C., by its compact habit; narrow, evergreen
foliage; showy racemes with multicolored flowers that
bloom sporadically throughout fall, winter, and spring; and
showy red new foliage.

BRIEF DESCRIPTION OF THE DRAWINGS

This new *Mahonia* is illustrated by the accompanying
photographs which show the plant's form, foliage and
inflorescences. The colors shown are as true as can be

2

reasonably obtained by conventional photographic proce-
dures. Colors in the photographs may differ slightly from the
color values cited in the detailed botanical description,
which accurately describe the colors of the new *Mahonia*.

FIG. 1 is a color photograph of a typical specimen of a
3-year-old *Mahonia* 'NCMH2' grown under standard horti-
cultural practices showing the inflorescences of 'NCMH2'
taken in October 2019 in Mills River, N.C.

FIG. 2 is a color photograph of a typical specimen of
Mahonia 'NCMH2' grown under standard horticultural
practices showing the flowers, habit, and new foliage color
of a two-year old plant of 'NCMH2' growing in Arden, N.C.
and taken in March 2019.

DETAILED BOTANICAL DESCRIPTION

Although *Mahonia* species are sometimes classified as
Berberis, the most recent taxonomic treatment by Yu and
Chung *Taxon* 66(6):1371-1392 (2017) classifies *Mahonia*
and *Berberis* as separate genera. The following is a detailed
description of the botanical characteristics of the new and
distinct *Mahonia* variety plant known by the denomination
'NCMH2'. All colors cited herein refer to The Royal Hor-
ticultural Society Colour Chart designations (The Royal
Horticultural Society (R.H.S.), London, Sixth Edition
(2016). Where specific dimensions, sizes, colors, and other
characteristics are given, it is to be understood that such
characteristics are approximations or averages set forth as
accurately as practicable.

The detailed descriptions reported herein were taken in
2019 from a three-year-old container-grown plant that was
grown in Mills River, N.C. under standard horticultural
practices. *Mahonia* 'NCMH2' has not been observed under
all possible environmental conditions; therefore, the pheno-
type may vary under different environmental conditions

such as season, temperature, light intensity, day length, cultural conditions, and the like, without however, any variance in the genotype.

TECHNICAL DESCRIPTION OF THE VARIETY

Classification:

Botanical name.—*Mahonia* ‘NCMH2’.

Common name.—*Mahonia*.

Variety name.—‘NCMH2’.

Parentage: Selected from a population of seedlings grown from an open-pollinated hybrid, NCSU H2009-018-063 (unpatented). The female parent, H2009-018-063, is a complex hybrid that includes *Mahonia eurybracteata*, *M. gracilipes*, *M. japonica*, and *M. lomariifolia* in its pedigree.

Plant description:

Growth habit.—Compact and upright shrub.

Growth rate.—Moderate.

Height.—About 100 cm.

Width.—About 60 cm.

Roots:

Type.—Fibrous.

Root color.—Moderate Yellow (RHS 160A).

Shoot and stem:

Lateral branch length.—Average is ~28 cm (~18 cm to ~44 cm).

Lateral branch diameter.—Average is ~0.8 cm (~0.5 cm to ~1.2 cm).

Internode length.—Average is ~5.4 cm (~3 cm to ~7.5 cm).

Immature shoot texture (current year).—Glabrous.

Immature shoot color (current year).—Yellow-Green (RHS 144A).

Mature stem texture (from prior year).—Glabrous with vertical fissures.

Mature stem color (from prior year).—Grey-Brown (RHS N199B).

Leaves:

Type.—Compound, odd-pinnate.

Persistence.—Evergreen.

Leaf fragrance.—None.

Leaf arrangement.—Alternate.

Leaf length.—Average is ~28 cm (~22 cm to ~34 cm).

Leaf width.—Average is ~11 cm (~8 cm to ~17 cm).

Rachis.—Length: Average is ~17 cm (~12 cm to ~22 cm). Width: About 0.2 cm. Color: Upper side Purple (RHS N77A), lower side Yellow-Green (RHS 144A). Texture: Glabrous.

Leaflet.—Arrangement: Opposite with a longer terminal leaflet. Number: 9 to 13 leaflets. Shape: Lanceolate. Apex: Long acuminate. Base: Cuneate. Venation: 3-nerved. Margins: Infrequently serrulate with 6 to 9 teeth. Sub-terminal leaflet length: Average is ~7.3 cm (~5 cm to ~11 cm). Sub-terminal leaflet width: Average is ~1.9 cm (~1 cm to ~2.5 cm).

Terminal leaflet length: Average is ~12.3 cm (~10 cm to ~17 cm). Terminal leaflet width: Average is ~2.2 cm (~1.4 cm to ~2.6 cm). Color: Emerging foliage, upper and lower surface: Strong Purplish Red (RHS 64C). Mature foliage, upper surface: Green (RHS 137A). Mature foliage, lower surface: Yellow-Green (RHS 146C). Texture: Glabrous. Attachment: Sessile.

Leaf attachment.—Petiolate.

Petiole.—Length: Average is ~1.4 cm (~0.7 cm to ~2.6 cm). Diameter: About 0.2 cm. Color: Yellow-Green (RHS 144A), both upper and lower surface. Texture: Glabrous.

5 Inflorescence:

Description.—Single flowers arranged on terminal racemes, opening from base to apex.

Number of racemes per terminal.—Average is ~8 (4 to 12).

Number of flowers per raceme.—30 to 50.

Flowering season.—October to March, sporadically, in Mills River, N.C.

Fragrance.—None.

Lastingness.—2 to 6 weeks.

Inflorescence.—Length: Average is ~12.3 cm (~10 cm to ~14 cm). Width: Average is ~1.8 cm (~1.5 cm to ~2.0 cm).

Flower.—Height: Average is ~0.5 cm (~0.5 cm to ~0.6 cm). Diameter: Average is ~1.4 cm (~1.3 cm to ~1.6 cm). Lastingness: 3 to 7 days.

Bud.—Shape: Rounded. Diameter, early stage: About 0.2 cm. Diameter, balloon stage: About 0.5 cm. Color, early stage: Vivid Reddish Orange (RHS 42A) with some Vivid Yellow (RHS 17C) and some Strong Reddish Purple (RHS 72B) towards the base. Color, balloon stage: Vivid Reddish Orange (RHS 42A) with increasing amounts of Vivid Yellow (RHS 17C) and some Strong Reddish Purple (RHS 72B) towards the base. Texture: Glabrous.

Petals.—Number: 6. Arrangement: Whorled. Length: ~0.5 cm. Width: ~0.3 cm. Shape: Ovate. Margin: Entire. Apex: Rounded. Base: Truncate. Color: Yellow (RHS 8A). Texture: Glabrous.

Sepals.—Number: 9, consisting of 6 petaloid sepals and 3 true sepals. Arrangement: Whorled. Petaloid sepals: Length: About 0.8 cm. Width: About 0.3 cm. Shape: Oblong. Margin: Entire. Apex: Obtuse. Base: Rounded. Color, inner surface: Yellow (RHS 8B). Color, outer surface: Yellow (RHS 8B) with some Vivid Reddish Orange (RHS 42A). Texture: Glabrous. True sepals: Length: About 0.5 cm. Width: About 0.3 cm. Shape: Ovoid. Margin: Entire. Apex: Acute. Base: Rounded. Color: Strong Reddish Purple (RHS 72B) at tips and Strong Purplish Red (RHS 63B) at base, both surfaces. Texture: Glabrous.

Peduncle.—Length: Average is ~12.4 cm (~6 cm to ~15 cm). Diameter: About 0.1 cm. Color: Greyed-Red (RHS 181C). Texture: Glabrous.

Pedicels.—Length: About 0.4 cm. Diameter: Less than 0.1 cm. Color: Greyed-Red (RHS 181C). Texture: Glabrous.

Reproductive organs:

Gynoecium.—Pistil number: 1. Pistil length: ~0.4 cm. Stigma shape: Round. Stigma color: Green-Yellow (RHS 1D). Style length: ~0.3 cm. Style color: Green-Yellow (RHS 1D).

Androecium.—Stamen number: 6. Stamen shape: Linear. Stamen length: About 0.4 cm. Anther shape: Two-lobed. Anther size: About 0.1 cm. Anther color: Yellow (RHS 7A). Amount of pollen: Moderate. Pollen color: Green-Yellow (RHS 1D).

Fruit and seed:

Fruit type.—Berry. Shape: Ovoid. Length: Average is ~0.6 cm (~0.4 cm to ~0.8 cm). Width: Average is

~0.4 cm (~0.3 cm to ~0.7 cm). Color: Greyed-Purple (RHS N186A). Texture: Glabrous, pruinose.

Seed.—Number: 1 to 2 per berry. Shape: Ovoid. Length: About 0.5 cm. Width: About 0.3 cm. Color: Yellow-Green (RHS 144C). Texture: Glabrous.

Disease and insect resistance: No significant disease or insect pests have been observed.

Cold hardiness: At least USDA zone 7A; testing has not been completed in colder zones.

COMPARISON WITH PARENTAL SPECIES

‘NCMH2’ is distinguished from *Mahonia x media* ‘Winter Sun’ in that ‘NCMH2’ has multicolored flowers of red (RHS 42A) and yellow (RHS 8B), whereas *Mahonia x*

15

media ‘Winter Sun’ has yellow (RHS 7B) flowers. ‘NCMH2’ is distinguished from *Mahonia* ‘Soft Caress’ (U.S. Plant Pat. No. 20,183) in that ‘NCMH2’ has wider evergreen sub-terminal leaflets (about 1.9 cm in width) with 5 reddish (RHS 64C) new growth, whereas *Mahonia* ‘Soft Caress’ (U.S. Plant Pat. No. 20,183) has narrower evergreen subterminal leaflets (about 0.4 to 0.8 cm in width) and green (RHS 144A) leaflets. ‘NCMH2’ also has racemes of multi-colored flowers, whereas *M. ‘Soft Caress’* has yellow (RHS 10 8A) flowers.

What is claimed is:

1. A new and distinct *Mahonia* plant named ‘NCMH2’ as illustrated and described herein.
